(57) CLAIM

The ornamental design for a phone purse wallet bag, as shown and described.

DESCRIPTION

FIG. 1 is a perspective view of the bag portion a phone purse wallet bag showing my new design;

FIG. 2 is a front view of the bag portion;

FIG. 3 is a front view of a phone purse wallet bag showing my new design;

FIG. 4 is a rear view of the bag portion;

FIG. 5 is a top view of the bag portion;

FIG. 6 is a bottom view of the bag portion;

FIG. 7 is a left side view of the bag portion;

FIG. 8 is a right side view of the bag portion;

FIG. 9 is a front view thereof showing a flap in an alternate position;

FIG. 10 is a top view thereof showing a flap in an alternate position; and,

FIG. 11 is a top view thereof showing a flap in an alternate position and showing environment.

The strap is not shown in FIGS. 1-2 and 4-11 for convenience of illustration.

The strap is shown broken away in FIG. 3 to indicate that no particular length is claimed and any portion shown in between forms no part of the claimed design.

The broken lines depict environmental structure and are included for the purpose of illustrating only and form no part of the claimed design.
